CLAIM

The ornamental design for a pill case, as shown and described.

DESCRIPTION

FIG. 1 is a perspective view of a pill case showing my new design;

FIG. 2 is front perspective view thereof;

FIG. 3 is a left side view thereof;

FIG. 4 is a right side view thereof;

FIG. 5 is a top plan view thereof;

FIG. 6 is a bottom plan view thereof;

FIG. 7 is another perspective view thereof;

FIG. 8 is a back perspective view thereof;

FIG. 9 is a perspective view when the lid is opened; and,

FIG. 10 is another perspective view when the lid is opened.

1 Claim, 10 Drawing Sheets
